UNITED STATES PATENT OFFICE

GEORGE HENRY THOMPSON, OF SELLY OAK, BIRMINGHAM, ENGLAND

PERCUSSION MECHANISM FOR TOOLS

Application filed March 30, 1928, Serial No. 265,925, and in Great Britain May 31, 1927.

This invention relates to improvements in percussion mechanism for use in percussion hand or other tools, such as chipping or de-scaling tools, riveting tools, concrete-breakers, road-breakers, coal-cutters, coal-borers, and the like. In such tools the percussion action of the operative head or drill is usually produced by one or more percussion members carried by a body or cage which is rotated 10 at a high speed, the percussion members being free to fly outwardly under centrifugal force as the body or cage rotates and to strike the operative head or a part associated therewith.

Considerable difficulty is experienced in designing and manufacturing percussion mechanism which will stand up to the heavy stresses involved without risk of breakage or rapid wear, and which at the same 20 time can be produced at a reasonable cost.

The object of my invention is to provide improved mechanism which is economical to produce and in which the weight of the rotary parts other than the percussion member or members is reduced to a minimum so that the stresses are correspondingly reduced. My improved mechanism also lends itself to very accurate machining and balancing of the rotating parts to reduce wear and vibration.

In percussion mechanism according to my invention percussion members in the form of solid balls are freely mounted in radial cylindrical bores in a body which is rotated through suitable gearing by any convenient power-driving means. In a hand tool the power may conveniently be conveyed to the mechanism by a flexible shaft. As the body rotates the balls are thrown outwardly in their bores and are adapted to strike the inner end of the tool or of a sliding plunger engaging the tool, the tool or plunger being preferably offset from the axis of the body so that the blows applied to the tool or plunger may be as nearly axial as possible.

Some practical forms of percussion mechanism in accordance with my invention are illustrated in the accompanying drawings in which:

Figure 1 is a longitudinal section through

one form of percussion mechanism in the plane of the axis of rotation.

Figure 2 is a longitudinal section in a plane at right angles to the axis of rotation.

Figure 3 is a section similar to that of Figure 2 but showing the use of two percussion balls.

Figure 4 is a similar section showing a modified arrangement of the balls.

Figure 5 is a longitudinal vertical section through a complete chipping tool embodying a simplified form of percussion mechanism.

Figure 6 is a section of the tool on the line 6-6 of Figure 5 but embodying the percussion mechanism illustrated in Figures 1 and 2.

In the mechanism illustrated in Figures 1 and 2, 1 is a percussion member in the form of a solid steel ball which is freely mounted in a tubular bore 2 in the hollow cylindrical housing or body 3. This body may be a steel tube but is preferably machined from the solid. The body is bored from one end nearly through to the other end, and the bore is then finished by a tool which leaves an inwardly projecting flange 4 around a central opening 5, the inner face of the flange 4 having substantially the same contour as the ball for which it forms a stop. Screwed into the open end of the bore is a plug 6 which is keyed in position after the mechanism is assembled by a taper pin or key 7 driven through the body and plug. Alternatively the plug 6 may be locked by a set-screw.

The plug 6 has an inwardly projecting reduced boss 8 with a concave end to receive the ball and form a stop for its inward movement. The length of this boss is such that the ball under rebound or when the mechanism is at rest cannot move inwardly far enough for its centre of gravity to pass the axis of rotation of the body, and the ball must always be thrown outwardly by centrifugal force towards the same end of the body.

To cushion the inward movement of the ball under rebound a coiled spring 9 may be arranged in the annular space between the boss 8 and the body, the end of the spring which receives the ball projecting a short distance beyond the end of the boss. An axial hole

- 10 is drilled through the plug and boss to release or admit air behind the ball, and a bore 11 of greater diameter is drilled in from the end of the plug to any desired depth to cause the weight of the plug to be such that it will exactly counter-balance the weight of the ball. Bearing pivots for the body are formed by diametrically opposed trunnions 12, 13 screwed into the walls of the body at the middle of its length and subsequently welded to the body as shown at 14. Each trunnion has a cylindrical part to receive a ball bearing in a suitable casing and one trunnion has a screwed extension 15 to receive a gear wheel or the like for driving the body. The central part of the body is preferably formed with a thickened band 16, and flat bosses are machined on this band around the holes for the trunnions to form abutments 20 against which the trunnions are welded. The ends of the body are machined to form portions of a cylindrical surface having the same axis as the axis of rotation of the body, as shown in Figure 2, and this machining 25 and the final machining of the trunnions are preferably effected after the trunnions have been secured in place to ensure perfect symmetry and truth of the rotating parts.
- In the mechanism illustrated the ball at 30 the outer end of its travel does not project beyond the peripheral surface of the end of the body, and a groove 17 is machined in each end of the body for the passage of the end of a reciprocating plunger or of the drill 35 or other tool which projects inwardly from a casing sufficiently far to be engaged by the ball on each revolution of the body. Alternatively the thickness of the flange 4 may be reduced so that the ball projects beyond the 40 periphery of the body and the groove 17 can then be omitted.
- In the modification illustrated in Figure 3, two balls 1, 1 are freely mounted in opposite ends of a hollow cylindrical body 18 at 45 each end of which is a curved inwardly projecting flange 19 corresponding to the flange 4. To permit of the machining of the interior of the body and of the inner faces of the flanges 19 the body is made in two parts, 50 one end 20 being screwed or forced on to the main part of the body. The junction is subsequently welded as shown at 21 to prevent any risk of unscrewing, or the two parts may be locked by a key or set-pin.
- 55 For the insertion and removal of the balls a clearance opening is formed in the side of the body at the middle of its length, and is normally closed by a removable plug 22. This plug may be screwed into the opening as shown or it may be a stepped or coned disc, the periphery of the opening being of complementary form. In either case the plug has an integral axial rod 23 which passes diametrically through the body, and its extremity is screw-threaded to receive a nut

24 which is screwed home against the body to lock the plug 22 in place. The part of the rod 23 within the body forms a central stop for the inward movement of the balls.

In the modification illustrated in Figure 4 70 the rod 23 is omitted and a helical compression spring 25 is interposed between the balls. This spring can be inserted by compressing it and passing it through the opening in the side of the body. As the spring will prevent 75 any risk of the balls passing out through the opening, no closure is necessary for the opening which may be a plain cylindrical hole 26.

To reduce the frictional grip of the spring 80 25 on the balls and to allow them to turn freely a pressure disc 05 or plate may be interposed between the balls and the ends of the springs as shown at one end of the spring in Figure 4.

The trunnion bearings for the mechanisms 85 illustrated in Figures 3 and 4 are identical with those described for the mechanisms illustrated in Figures 1 and 2 and need not be further described.

The incorporation of my improved percussion mechanism in a chipping or like percussion tool is illustrated in Figures 5 and 6. The mechanism is rotatably mounted in ball bearings in a casing 27 provided with a handle 28 for its manipulation, which handle 90 may be integral with the casing or suitably secured thereon. If desired springs may be mounted between the tool carrier and the body carrying the handle to relieve the operator of the shocks due to the percussion 95 action. A bevel wheel 29 mounted on one trunnion of the percussion mechanism meshes with a bevel wheel 29a driven by a flexible shaft 30 so that the percussion mechanism is continuously rotated. The bevel wheel 29 100 and the housing for the inner end of the flexible shaft are located in a subsidiary casing which is rotatable upon the main casing about the axis of the percussion mechanism so that the flexible shaft can be set at any 105 angle to the casing to facilitate the handling of the tool in a restricted space.

At one point there projects through the casing and into the path of the ball or balls of the percussion mechanism the inner end 110 of a sliding piston or plunger 31 which receives a blow from the ball or balls on each revolution. The axis of the plunger 31 is offset from the axis of the percussion mechanism as shown in Figure 5 so that the blow 115 is applied by the ball to the plunger in a direction as nearly axial as possible. The plunger is slidably guided in a cylindrical extension 32 of the casing and the chipping or other tool 33 is slidably guided in the outer 120 end of this extension, the inner end of the tool abutting against the outer end of the plunger so that the plunger transmits to the tool the blows received from the percussion mechanism. 125

In the percussion mechanism illustrated in Figure 5 an extremely simple construction is employed. A percussion ball 34 is freely mounted in a cylindrical recess 35 drilled 5 radially in a solid body 36 which is secured upon a rotatable spindle 37. A hole 38 is drilled diametrically through the body from the bottom of the recess to prevent the movement of the ball from being retarded by air 10 pressure behind it.

As the body rotates the ball is thrown outwardly by centrifugal force and travels in a groove 39 of curved cross-section formed in the inner face of an annular liner 40 of 15 hardened steel secured in the casing around the body, and the inner end of the plunger 31 projects through this liner so that it is engaged by the ball. The chord of the curve of the groove 39 and the diameter of the ball 34 20 are substantially greater than the diameter of the plunger 31 so as to allow the ball to ride freely over the plunger hole without fouling when the tool is not held against the work.

Only one ball has been shown in Figure 5 25 but obviously two or more balls may be employed by providing a suitable number of radial recesses in the body to house the balls.

I claim:—

1. Centrifugal percussion mechanism for 30 percussion tools comprising a casing, a body rotatably mounted in the casing, a stationary ring surrounding said body, an annular groove of curved cross-section in the inner 35 face of the ring, a slidably mounted offset striker projecting through the ring, a radial cylindrical bore in the body, and a ball member freely mounted in the bore, said ball member when thrown outwardly by centrifugal force being adapted to travel around 40 the groove in the ring and to engage the end of the striker.

2. Centrifugal percussion mechanism for 45 percussion tools comprising a casing, a rotatable body, a radial, cylindrical bore in the body, a ball member freely mounted in the bore, and an inwardly projecting flange at the outer end of the bore to form a stop for the ball member, the inner contour of the flange conforming substantially with that of 50 the ball, the body being provided with means for introducing the ball laterally into the bore.

3. Centrifugal percussion mechanism for 55 percussion tools comprising a casing, a rotatable, tubular, cylindrical body, bearings for the body at right angles to its longitudinal axis, a plurality of ball members freely mounted in the tubular body, a unitary, resilient stop interposed between the balls in 60 the tubular body to limit the movement of the ball members inwardly within the body, and means for introducing the balls and stop in the bore.

4. Centrifugal percussion mechanism for 65 percussion tools comprising a casing, a ro-

tatable, tubular, cylindrical body, bearings for the body at right angles to its longitudinal axis, a ball member freely mounted in the tubular body, and a lateral opening in the body constituting means for the insertion and removal of the ball member. 70

5. Centrifugal percussion mechanism for 75 percussion tools comprising a casing, a body rotatably mounted in the casing, a radial, cylindrical bore in the body, a ball member freely mounted in the bore, the body being provided with a stop to prevent the outward escape of the ball from the bore, and with readily removable means for permitting the removal or the insertion of the ball behind the stop, and an offset striker member slidably mounted in the casing and projecting into the path of the ball member. 80

6. Centrifugal percussion mechanism for 85 percussion tools comprising a casing, a rotatable body, a radial, cylindrical bore in the body, a ball member freely mounted in the bore, the body being provided with stops to limit the movement of the ball member in both directions within the bore, and with readily removable means for permitting the removal or the insertion of the ball between 90 the stops, and bearings for the body at right angles to the longitudinal axis of the bore.

7. Centrifugal percussion mechanism for 95 percussion tools comprising a casing, a rotatable body, a radial, cylindrical bore in the body, a ball member freely mounted in the bore, the body being provided with a stop to arrest the outward movement of the ball member and with a stop to arrest the inward movement of the ball member towards the axis of rotation of the body, so that the centre of gravity of the ball member cannot pass that axis, and with readily removable means 100 for inserting the ball between the stops. 105

8. Centrifugal percussion mechanism for 110 percussion tools comprising a casing, a rotatable body, a radial, cylindrical bore in the body, a ball member freely mounted in the bore, a resilient stop in the bore behind the ball member to cushion its rebound, and readily movable means for introducing the resilient means and the ball into the bore.

In testimony whereof I affix my signature. 115
GEORGE HENRY THOMPSON.
